GUARD FOR USE IN PAINTING AND
CLEANING OPERATIONS

John Samuel Lister, Montreal, Quebec, Canada

Application February 10, 1947, Serial No. 727,574

2 Claims. (Cl. 91—65)

1

This invention relates to improvements in guards for use in cleaning and painting operations and the primary object of the invention is to provide a convenient and effective device for use, while applying paint or other compound to one surface, to mask an adjoining surface and protect the same against inadvertent application of paint or other compound thereto. A further object is to provide a device, as aforesaid, particularly adapted for use in corners. A still further object is to provide a device, as aforesaid, so constructed as to prevent paint or other liquid from being drawn by capillary action between the device and the surface desired to be protected thereby. Various other objects and the advantages of the invention may be ascertained from the following description and the accompanying drawings.

Where two or more surfaces meet at an angle, for example, a surface of window glass and one or more surfaces of window sash, or a wall surface and the edge surface or surfaces of door, window or like trim, it is difficult to apply paint or other compound to one of the surfaces without inadvertently applying it to the other surface. The present invention provides a device adapted to overcome the aforesaid difficulty in any situation in which it may be ordinarily encountered.

The invention consists, broadly speaking, in a masking element for one or more surfaces to be protected, having edges in angular relation to one another adapted for engagement with one or more surfaces to be treated.

In greater detail, the invention consists in the features and combinations of features herein disclosed, together with all such modifications of detail and substitutions of equivalents therefor as are within the scope of the appended claims.

In the accompanying drawings which illustrate that embodiment of the invention now preferred, but to the details of which the invention is not limited:

Fig. 1 is a perspective view of the guard of my invention.

Fig. 2 is a plan view of the guard of Fig. 1.

Figs. 3 and 4 are end elevations of the guard as viewed from the left hand and right hand ends, respectively, of Fig. 2.

Fig. 5 is a front elevation of the guard.

Figs. 6 and 7 are sectional views of the guard, on an enlarged scale as compared with preceding figures, showing modifications.

Referring more particularly to the drawings, 11 designates a substantially flat body comprising arms 12 and 13 forming an L-shaped structure and 14 designates a wing at the opposite end of

the arm 12 from the arm 13, lying in a plane perpendicular to the plane of the arms. The body is provided with a handle 15 of any suitable shape, preferably extending lengthwise of the arm 12 and attached at one end to the body 11 and at the other end to the wing 14, whereby the handle supports the wing against displacement with reference to the body. Preferably, the arm 13 and the wing 14 are formed integral with the arm 12 and extend equal distances therefrom.

The outer edges 16 and 17 of the arms 12 and 13, respectively, are formed at an angle of approximately 90° to one another and the inner edges 18 and 19 of the arms are parallel, respectively, with the edges 16 and 17. The free end edge 20 of the arm 13 may be at any desired angle to the edges 17 and 19 but is preferably formed at an acute angle, for example 60°, to the edge 19. The upper edge 21 of the wing 14 may be in any desired relation to the plane of the body but is preferably parallel therewith, while the end edge 22 of the wing is formed at a normal or at an acute angle to the plane of the body and meets the extremity of the arm edge 16. The remaining end edge 23 of the wing is preferably formed at an acute angle to the edge 21. The lower edge 24 of the wing beyond the arm 12 is preferably spaced above the plane of the lower surface of the arm, as shown in Fig. 3, so that it will not contact freshly applied paint as the device is moved.

The edges 16 to 20 of the arms are bevelled from the upper surfaces of the arms to provide, substantially, knife edges at the lower surfaces 35 of the arms. The edges 21 to 23 of the wing are likewise bevelled from the inner surface of the wing, adjacent the arm 12, to provide knife edges at the outer surface of the wing.

The lower surfaces of the arms 12 and 13 and the outer surface of the wing 14 may be flat, unbroken surfaces but are preferably recessed from the edges inwardly, so that when the guard is applied to a surface to protect the same, contact is made only at the edges, thereby to prevent liquid being drawn between the guard and the protected surface by capillary action, as might occur if there was surface to surface contact. The recessing of the surfaces may extend from edge to edge, as shown at 25 in Fig. 6, or may be merely a groove extending inwardly from and along the edges, as shown at 26 in Fig. 7.

In using the device, the operator holds the guard by its handle and presses the arms or the arms and wing against the surface or surfaces 55 to be masked, with one or more of the edges

16 to 23 in contact with the surface or surfaces to be treated, at the junction thereof with the surface or surfaces masked. Paint or other composition may be applied to the unmasked surface or surfaces without danger of smearing the masked surface. The various angular relations of the edges adapt the device for use under all conditions ordinarily encountered. The L-shape of the device adapts it for work in both inside and outside corners while the non-normal relation of certain of the edges enables the device to be used in corners where the contained angle is less than 90°. In cases where three surfaces meet, of which two are to be protected, the arm 12 and wing 14 are held against these 15 surfaces. The inclination of the wing edge enables a guard with no recessing of its outer surfaces, to be held at a small angle to the masked surface so that contact is obtained only at the edge 16, thereby to prevent liquid entering by 20 capillary action between the guard and the masked surface.

The device may be formed of any suitable material such as metal or resinous plastics, by pressing or moulding or in any other suitable way.

Having thus described my invention, I claim:

1. A guard for use in painting or cleaning comprising a substantially flat, oblong body; a lateral extension from one end portion of said body, lying in the plane of the body and having its opposite edges parallel and lying at angles of 90° to the long edges of the body and its end edge at an acute angle to one of its said opposite edges; a wing at the other end of said body, 30 lying in a plane normal to the plane of the body and to the long edges thereof and projecting laterally beyond the body in the same direction

as the said extension, the upper and lower edges of said wing being parallel to the plane of the body and the end edges being inclined with respect to the plane of the body.

5. 2. A guard for use in painting or cleaning comprising a substantially flat, oblong body; a lateral extension from one end portion of said body, lying in the plane of the body and having its opposite edges parallel and lying at angles of 90° to the long edges of the body; a wing at the other end of said body, rigidly connected to the body and lying in a plane normal to the plane of the body and to the long edges thereof and projecting laterally beyond the body in the same direction as said extension, the upper and lower edges of said wing being parallel to the plane of the body; and a handle rigidly connected to the wing and to the body at a point remote from the wing and supporting the wing rigidly with respect to the body.

JOHN SAMUEL LISTER.
